(57) **CLAIM**

I claim the ornamental design for a hooded wrap, as shown and described.

DESCRIPTION

FIG. 1 is a perspective view of a hooded wrap, showing my new design, illustrated in a closed configuration around a person;

FIG. 2 is a front elevational view thereof, illustrated in an open configuration;

FIG. 3 is a rear elevational view thereof, illustrated in the open configuration;

FIG. 4 is a left-side elevational view thereof, the right-side elevational view being a mirror image thereof;

FIG. 5 is a top plan view thereof, illustrated in the closed position; and,

FIG. 6 is a bottom plan view thereof, illustrated in the closed position.

The broken lines showing a person in FIG. 1 are included for the purpose of illustrating the invention in use, and form no part of the claimed design. The remaining broken lines represent stitching and are part of the claimed design.
